BURNHAM C. STICKNEY, OF RUTHERFORD, NEW JERSEY.

INTERNAL-COMBUSTION ENGINE.

Application filed September 12, 1923. Serial No. 662,198.

This invention relates to rotary valve mechanism for engines; more particularly those of the internal combustion class.

It is sought to produce an organization which minimizes or avoids the objections which are usually inherent in rotary valves, including the difficulty of friction, binding and seizing of the valve, which may be due to the unsupported pressure at the compression and explosion strokes, or to unequal heating and expansion of the valve and the co-operating ported devices, or other causes.

Another feature is the provision of improved means for quickly opening and quickly closing intake and exhaust ports in combustion chamber and valve chest, and to provide for a much enlarged capacity of the ports as compared with those usual in rotary valve engines.

20 The improved rotary valve is in the nature of a shutter comprising complementary oppositely-revolving ported shells or elements fitted one within the other to form a composite shutter or valve which surrounds and fits the cylindrical wall of a ported explosion chamber; said composite shutter or valve being itself fitted within a ported casting or valve chest; the chamber and the chest each provided with both intake and exhaust ports, all controlled by the one composite valve.

25 The valve is pressure-balanced; and for the purpose of securing such balance, the intake and exhaust ports in the explosion chamber are placed at diametrically opposite sides thereof, so that the outer pressure of the gas through one port upon the valve is balanced by similar opposite pressure through the opposite port; this result being secured, in a valve composed of oppositely-revolving complementary nested shells, by placing the exhaust and intake ports both on one side of each shell and making one of the shells right and the other left.

30 The composite valve has the characteristic of automatically expanding and contracting its intake and exhaust ports. The intake port in the explosion chamber is opened by the expansion of the composite intake port in the valve, and it is closed by the contraction of said composite intake port; and the exhaust port in the explosion chamber is thereupon opened by the expansion of the exhaust port in the composite valve, and eventually closed by the contraction of said composite exhaust port in the valve.

The expansion and contraction of the composite valve ports are rapid. Moreover, the explosion chamber ports may be made of double the angular extent usual in rotary engines. All of the advantages of balanced pressure, rapid opening and closing and extraordinary capacity of the combustion chamber ports, are secured by a single simple organization.

35 Friction, binding and seizing are minimized or eliminated, by overcoming the unequal heating and expansion of the composite valve and its mounting. The explosion chamber, around which the valve fits, is hollow walled, and water is circulated therein from the detachable engine head and thence to the usual radiator, so that overheating of the composite valve is avoided, and hence the parts of said valve may be closely fitted together and to the stationary ported members. Since the water flows between the inner walls of the explosion chamber and the composite valve, the latter is but little exposed to heat, and its temperature may therefore be kept moderate by contact with the cooled walls of the explosion chamber, and of the valve chest. The latter is preferably integral with the chamber, an annular well being formed between them to constitute a seat in which the composite valve rotates.

40 The detachable head of the engine comprises preferably a hollow or box-like base forming a water-jacket, which is in communication with the water-jacket or jackets of the engine block, and is also in communication through the hollow walls of the explosion chambers with the radiator, thus tending to secure uniformly low heat of the valves and associated parts for the various engine cylinders. A feature of the invention is the use of a single casting for the detachable engine head, the row of valve chests, the domes within said chest forming the explosion chambers, and preferably also the intake and exhaust manifolds between which the row of valve chests extends, each valve chest opening into both manifolds on its opposite sides.

45 Other features and advantages will hereinafter appear.

In the accompanying drawings,

50 Figure 1 is a sectional elevation of a valve mechanism for an internal combustion engine embodying the present improvements in one form.

Figure 2 is a diagrammatic cross-section or plan of the complementary members of the composite valve to illustrate the cycle of operations thereof.

- 5 Figure 3 is a part-sectional longitudinal elevation of the improved detachable engine head with its appurtenances, and Figure 4 is a plan of the same with parts broken away.
- 10 Figure 5 is a sectional diagrammatic plan, showing in the upper row of valve chests a section taken through the fixed intake ports, and showing in the lower row a section taken through the fixed exhaust ports of the 15 same chests, the same valves and the same explosion chambers as in the upper row. The upper row shows the positions of the intake ports in the various complementary valve shells at the middle portions of the 20 strokes of their respective pistons; and the lower row is a similar showing regarding the exhaust ports in said complementary valve shells or members.

At Figures 6 to 9 are illustrated various 25 positions of the complementary or interdependent inner and outer shells or members of the same valve, illustrating the expanding and contracting characteristics of the valve ports, and showing how the intake 30 and exhaust ports in the explosion chamber are kept closed by the co-operation of the oppositely-revolving complementary members of the composite valve except during the intake and explosion strokes of the 35 piston.

Figures 10 and 11 are diagrammatic sectional plans to show lag and lead of the valve at various points.

Figures 12 and 13 correspond with Figures 6 and 8, but illustrate the direction of each member of the valve as opposite from that shown in Figures 6 and 8.

Figure 14 is a perspective view of the inner shell or shutter forming one of the 45 complementary or interdependent members of the composite valve, with one form of driving gear therefor, and Figure 15 shows a similar view of the outer shell forming the other member of said valve.

50 There is illustrated a conventional engine block containing a multiplicity of vertical cylinders 20 and comprising a water-jacket 21, each cylinder containing a piston (shown diagrammatically at 22 above its true position, which should be midway of its exhaust 55 stroke). Upon the cylinder block there may be attached, by means of bolts 23 for example, an improved engine head 24, preferably jacketed or containing a water space 60 25, the latter being a box-like structure and extending throughout the length of the engine head and communicating by numerous passages 26 with water spaces 27 in the engine block, so that the cooling water which 65 is pumped into the engine block may flow

up through the passages 26 into the engine head, and thence, in a manner presently described, back to the radiator.

Integral with the engine head 24 is a series of erect ported domes or enclosures 70 forming combustion chambers 28, closed at their upper ends and opening at their lower ends into the respective cylinders 20, one combustion chamber (or gas conduit) for each cylinder. These fixed combustion chambers or devices may be of cylindrical or other suitable interior contour, and may serve to conduct the gases into and out of the engine cylinders, and even if of very small internal diameter (as compared with the engine cylinders) they may still have sufficient capacity for this purpose.

Fitted around each combustion chamber are oppositely rotating turret-like ported 75 complementary valve portions in the form of nested shells 29, 30. Valve shell or portion 29 fits closely to the surface of the outer cylindrical member or dome 32 of the combustion chamber, and valve portion or shell 30 fits closely to the outer cylindrical surface of shell 29. Valve shell 30 also fits closely within a ported enclosure, housing, casing or chest 31, which may be of cylindrical interior contour and of any suitable exterior form. Neither of these shells or 80 portions by itself (as will presently be evident) serves as a complete valve, but both shells co-operate to open the explosion chamber, and also co-operate to close the same.

At two stages the intake port of the explosion chamber is partly closed by one shell and partly closed by the other shell. This 85 situation occurs at the beginning of the compression stroke and at the end of the explosion stroke. The oppositely rotating shells are therefore complementary one to 90 the other to make a single complete rotary valve which is inserted like a shutter between the ported wall of the explosion chamber and the ported wall of the valve chest.

The complete valve therefore is in the nature of a pressure-balanced revolving shutter fitting between the fixed ported outer and inner walls of the chest, and having 95 automatically expanding and contracting 100 ports for rapidly opening and rapidly closing the double-size or capacious inner and outer fixed ports. Owing to such port expansion and contraction, each fixed port in 105 chest and chamber is opened or closed at 110 twice the angular speed of either valve shell. The complementary shells therefore fit down in a ported annular well 40, which 115 is formed in the general casting, Figures 1 and 4.

The inner wall 28 of the explosion chamber may rise directly from the floor plate 25^a of the engine head, while the outer wall 32 may rise from the top plate 25^b of the engine head, the spaces between said inner 120 and outer walls being filled with a 125

130

The inner wall 28 of the explosion chamber may rise directly from the floor plate 25^a of the engine head, while the outer wall 32 may rise from the top plate 25^b of the engine head, the spaces between said inner

and outer walls, together with the space 33^a between the lower plate 25^c of the hollow top of the flame chamber and the upper plate 34 thereof, forming a water course, 5 which opens into an uptake or discharge 35.

In other words, the combustion chamber 28 may be formed with a water-jacket 25, or may be double-walled and double-topped, forming the water spaces 33, 33^a, all of 10 which are in open communication with one another and with the main water space 25 in the engine head; and from the water-jacket, which includes the chest 31 with its top 34, there may rise the central discharge 15 pipe 35, attached at its top by a nipple 36 to a main 37, for discharging the heated water from the engine into the usual radiator (not shown). Thus the water passing up from the engine block may flow along 20 the engine head, and pass up through the hollow-walled combustion chamber and escape through the outlet 35 to the discharge conduit 37, whereby the exterior walls 32 of the combustion chambers are kept relatively 25 cool; the difference of temperature and hence the extent of relative expansion of the inner and outer revolving shells, as well as of the explosion-chamber walls and the valve chest 31, being minimized or practically 30 eliminated, so that liability of binding or friction of the nested complementary valve shells is reduced to a negligible point.

One of the advantages of the invention, as to certain of its features, is that a single 35 inexpensive and compact casting may include the double-walled combustion chambers 29, 32, 25^c, 34, the valve chests or casings 31, and the hollow or box-like engine head 25, as well as an intake manifold 38 and 40 an exhaust manifold 39; the line of upstanding valve chests 31 extending between these manifolds, each of which has a multiplicity of ports at the points where it joins into the valve chests. The exhaust manifold may be 45 spaced from the engine head, to favor radiation of heat. Although each combustion chamber is hollow-walled and hence of relatively large exterior diameter, it still may accommodate valves of relatively small diameter, as compared with the engine cylinders, and the composite valves may turn in 50 stationary bearings, and may be simple, light and inexpensive, and capable of being readily assembled and disassembled, and the 55 bearings as well as the valve shells themselves may be closely and smoothly fitted. All of the inlet and exhaust ports, of which details are presently given, may be of relatively large capacity, to give maximum efficiency to the engine.

The invention may be also practiced by reversing the flow of water, that is, the main 37 may be connected to receive water through the pump (not shown) from the 60 lower end of the radiator; while the bottom

of the water-jacket 27 in the engine block may be connected to discharge into the top of the radiator, so that the flow of cooled water may be downward from the main 37, first through the valve chests and then 70 through the cylinder block. By this method the heat of the valve chest and composite valves may be still further reduced if desired.

The complementary valve shells preferably 75 form inverted cups nested the one closely within the other. Certain features of the invention may be practiced by using forms other than cylinders for the nested valve shells surrounding the explosion 80 chamber within the valve chest; but, where cylinders are employed, they may comprise disk-like tops 47 and 50 integral respectively with the valve shells. These tops may serve to support the shells and prevent 85 the lower gas-tight edges thereof from wearing away; and they may also aid in preventing leakage, and also serve to connect the valve shells with bearing hubs of relatively 90 small diameters.

The complementary valve shells in each 95 nest or pair may be rotated in opposite directions by means of any suitable gear train, as, for example, by the use of a sprocket chain 41, connected to the crank shaft (not shown) of the engine and running over a sprocket wheel 42, which may revolve once to each revolution of the crank shaft. This sprocket wheel may be placed upon a driving shaft 43, working in a bearing provided 100 in an end of gear box 62, and having a beveled pinion 44 to mesh with a beveled gear 45, the latter fixed upon a vertical hollow hub 46 rising from the stop 47 of the inner valve shell 29, and also meshing with a beveled gear 48 fixed upon a hub 49 rising from the top 50 of the outer valve shell 30, whereby the complementary shells are revolved in opposite directions simultaneously at uniform 105 angular speed. A driving train of similar gears 51 may connect all of the hubs 46 of the inner valve shells; and a similar train 52 may connect all of the hubs 49 of the outer valve shells, so that all of the shells may revolve constantly at uniform speed, those in each assemblage revolving one oppositely from the other. Any other train of gearing may be employed to revolve the valve shells in each nest oppositely from each other at half the speed of rotation of 110 the crank shaft; and it is also obvious that if desired the outer shells may all revolve in the one direction, while the inner shells may all revolve in the opposite direction.

The water vent which preferably surrounds the explosion chamber may serve not only to conduct the water from the course between the walls of said chamber, but may also serve as a bearing of relatively small 115 diameter for the hub 46 of the inner valve 120 shell 29, and also as a bearing for the hub 49 of the outer valve shell 30. The water vent 125 may also serve as a bearing for the hub 46 of the inner valve shell 29, and also as a bearing for the hub 49 of the outer valve shell 30.

shell, and thus permit the use of a hub 49 of relatively small diameter for the outer valve shell; these hubs being adjacent to the gears, so that operating friction may be minimized. The invention, however, is not limited to timing gears at these points.

The inlet manifold 38 is ported at 53, and from these ports passages 54 lead into the combustion chambers 28. The exhaust manifold 39 is also ported at 55, and from these ports passages 56 lead into the combustion chambers.

The ports 54, 56 where they open into the explosion chamber or gas conduit 28 are illustrated at lower levels than where they open into the manifolds, these passages being inclined outwardly and upwardly. This permits the vertical capacity of the explosion chamber to be reduced, while permitting the valves to set up above spark plugs 57, and also above the top of the hollow engine head.

The spark plugs 57 may be of any suitable construction, and may, for example, be inserted in sockets 58 formed in the side of the engine head below the intake manifold, and opening into pockets 59, of which one is provided for each cylinder; the pockets opening into the explosion chambers 28 near their lower ends.

To close the tops of all the valve chests there may be arranged a cover plate 60, detachably secured by screws 61, this plate forming the bottom of a box 62, to contain the valve gearing. The box may have a removable lid 63.

The inner rotary complementary shell 29 in each valve may be pressure-balanced, that is to say, provision is made whereby outward gas-pressure produced thereon through ports 54 and 56 at both the compression and explosion strokes is sustained by said complementary shell in a manner to minimize or obviate the tendency of the shell to bind or grip because of such pressure of the gas.

To this end several steps are taken, one of which is to form the inlet and outlet ports or passages upon opposite sides of the gas-chamber 28, as at 54, 56, so that pressure within either passage outwardly in one direction against inner valve shell 29 is balanced by like outward pressure in the opposite passage 54 or 56. Another step is to make the area of the inlet port 54 in the explosion chamber substantially equal to the area of the outlet port 56, so that the outward pressure at either side upon the inner valve shell balances the pressure at the other side. Another step is to divide one of the passages or ports (preferably the intake) into equal upper and lower portions 54, while at the opposite side of the explosion chamber the passage 56 occupies a midway position between these intake portions 54. There is therefore little or no tendency to skew the

inner complementary valve shell in its bearings, or to cause it to press more at one point than at another, or to wear unevenly.

Referring to Figures 1 and 14, the inner complementary turret-valve shell 29 has upper and lower inlet ports 64 for opening and closing the fixed intake ports at 53, 54. The valve shell 29 at its side has a midway single port 65 for opening and closing the fixed exhaust ports 55, 56 of the valve chest and explosion chamber. The combined area of valve shell ports 64 may be approximately equal to the area of 65, to agree with the ports in the valve chest, whose position and area have just been described; the port 65 (considered vertically) being midway of the ports 64. The outer complementary turret-valve shell 30 may have inlet ports 66 corresponding with 64 and a midway outlet port 67 corresponding with 65.

The exhaust port is in a different zone from the upper and lower intake ports, so that no exhaust port in a composite valve can open an intake port in the combustion chamber. Moreover, no intake port in a valve can open an exhaust port in the combustion chamber.

The combustion chamber 28 is closed at the compression and explosion strokes, while it is open at the exhaust and intake strokes. While the intake stroke immediately follows the exhaust stroke of the engine, but for pressure-balancing purposes, still the inlet ports in the combustion chamber are formed diametrically opposite from the combustion ports (in place of being in juxtaposition thereto, as is the usual practice), so that the internal pressure against one wall of said inner valve shell may be balanced by the internal pressure against the opposite wall thereof. The combustion chamber is opened at one side immediately following the explosion stroke, and at the opposite side immediately following the exhaust stroke.

At Figure 15 a similar description applies, except that this outer shell of the composite valve turns to the left, and the arrangement of its exhaust port is opposite from the arrangement at Figure 14. Throughout all the valve shells each exhaust port immediately follows the intake port as the shell is revolved. There are illustrated both right and left-hand inner valve shells, and both right and left-hand outer valve shells; although, by using other trains of gearing, the inner shells may, if desired, be all right-hand and the outer shells all left-hand.

A feature of the invention is the ample capacity of the ports in the chest and explosion chamber (each port may extend about 90 degrees around the chamber) and the great speed with which each of such ports is opened and closed. Owing to the doubled capacity of these ports, the outward pres-

sure of the exploding charge upon the inner valve shell is doubled, and this serious difficulty is overcome because the chest and explosion chamber ports are so placed as to secure a balance of the pressure exerted against the inner valve shell.

By placing the ports in angular juxtaposition in each valve shell, with the exhaust port immediately following the intake port, it follows that at the conclusion of the co-operative exhaust-closing movement of the rotary shells at one side of the explosion chamber, there begins the co-operative intake-opening movement of the same at the opposite side of the explosion chamber. It will therefore be seen that opposite arrangement of the explosion chamber ports is secured, resulting in balance of gas-pressure upon the inner valve shell, which therefore revolves freely notwithstanding its exposure to pressure through both exhaust and intake ports of the explosion chamber, these ports being of doubled area or capacity as compared with usual explosion chamber ports.

Any explosion chamber port is opened by the drawing apart of the vertical valve edges as the latter occupy positions midway of the fixed port openings. The fixed port is likewise closed by the valve edges approaching each other at the middle of the fixed ports.

Each port in the engine head may be about 90 degrees in extent, and the same may be true of each port in each valve shell. At Figure 14 the valve-shell ports are illustrated as each 90 degrees in extent; and it will be seen that the exhaust port 65 immediately follows the intake port or ports 64 around the shell 29. Inasmuch as the exhaust port 56 is diametrically opposite from the intake ports 54 in the explosion chamber 28, it follows that when the following edges of the exhaust ports in the oppositely revolving valve shells 29 and 30 approach and finally reach the middle of the exhaust port 56 in the explosion chamber 28 (thereby co-operatively closing the same), the leading edges of the intake ports 64 and 66 begin to separate, and hence co-operate to open the intake ports 54 in the explosion chamber. The exhaust and intake ports are all on the same side of the valve shell, and taken together may occupy one-half of the circumference thereof, whereby the following edge of the exhaust port is diametrically opposite from the leading edges of the intake ports. Hence said edges may simultaneously occupy closed positions on line M—M, Figure 2, midway of the exhaust and intake ports in the explosion chamber. It will be understood that the closing of an explosion-chamber port occurs at the middle line thereof by the co-operation of the complementary inner and outer valve-shells, and that simultaneously the opening of the ports on the opposite

side of the explosion chamber may occur at the middle line M—M thereof by the co-operation of said valve shells.

At Figure 2 there is illustrated diagrammatically the operation of completing the closing of the exhaust ports 55, 56 in a valve chest and explosion chamber, and at the same time beginning the opening of the opposite intake ports 53, 54 in the same; it being borne in mind that the closing is completed and the opening is begun along the middle line M—M of the chest ports. It will be seen at this figure that the exhaust port 67 occupies the lower right-hand sector of the outer valve shell 30, which is revolving to the left. Its following edge has just reached the middle line M—M of the chest port. The exhaust port 65 in the inner valve shell, which is turning to the right, is indicated by dotted lines; and it will be seen that this port 65 has just completed its movement past said middle line M—M of the chest port. Hence the following edges of these exhaust ports in the complementary outer and inner valve shells complete the closing of the combustion-chamber port 56, and the chest port 55. In other words, the intake opening of the composite valve has rapidly contracted and finally closed up over the exhaust port 56 of the explosion chamber, at line M—M. At this time the intake port 54 of the explosion chamber begins to open, inasmuch as the leading edge of the intake port 64 of the rotating inner valve shell 29 passes said middle line M—M of the port 54, and the leading edge of the intake port 66 (shown by dotted lines) in the oppositely revolving outer valve shell 30 is just moving to the left from said middle line M—M. Hence said leading edges of the inner and outer valves recede rapidly from each other over the intake port 54, to open the same.

In the diagrammatic plan at Figure 5, the line of upstanding valve chests 31 is shown in section through the fixed intake ports 53, 54. The four chests are marked A, B, C, D. At A the fixed intake ports 53, 54 are closed by the body of the inner valve shell 29, that is, the portions of the shell which are immediately above and below the midway port 65. Each valve shell may for some purposes be considered as composing three zones, namely, a narrow upper inlet zone, a broad midway exhaust zone, and a narrow lower inlet zone; and each of these zones is provided with a port. In each of the engine cylinders it will be understood that the pistons 22 are supposed to be about midway of their strokes; the piston associated with chest A being midway of its explosion stroke.

The piston associated with chest B is understood to be about midway of its compression stroke. In this the fixed inlet ports 53, 54 are closed.

In chest C the fixed ports 54, 55 are also

closed, the piston being midway of the exhaust stroke; the order for firing being A, B, D, C.

In chest D all of the intake ports 53, 54, 55, 64, 66 are fully open, the piston being midway of its intake stroke.

Figure 5 also, in a lower row, shows diagrammatically a plan of the chests A, B, C, D, in section, taken through the exhaust ports 55, 56 about midway of the valve chests. In the lower row the valve shells are seen in their identical positions as in the upper row of chests. The upper row shows the intake ports, and the lower row 15 the exhaust ports of the same valve shells and chests. In the lower row it will be seen that at A, B and D the exhaust ports 55, 56 are closed, while at C the exhaust ports 55, 56 are open; exhaust taking place through 20 chest C while chest D is taking in a new charge.

Figure 6 shows diagrammatically successive positions of the intake ports 64 and 66 in the oppositely revolving inner and 25 outer valve shells or elements 28, 29. The stationary ported explosion chamber is indicated by an arc 29 ported at the top at 54. Two arcs 28 and 29 indicate the inner and outer valve shells. There are shown 30 successively the positions of the same valve shells at the beginnings of the piston strokes for intake, compression, explosion and exhaust. In every case the intake port 54 is closed; said port being shown as about to be 35 opened at the first diagram in this figure, and as having just closed in the second diagram, and as remaining closed in the last two diagrams.

In Figure 7 the positions of the same 40 revolving valve shells or elements correspond with those at Figure 6, except that in Figure 7 the valve elements are shown in the positions that they occupy when the piston is midway of its respective strokes. 45 The explosion-chamber intake port 54 is fully opened in the first diagram, and closed in the remaining diagrams.

In all of Figures 6 to 9, the same complementary valve shells are shown, Figures 6 50 and 7 showing the intake ports in said valve shells, and Figures 8 and 9 showing the exhaust ports in the same valve shells. Figures 8 and 9 also show the exhaust port 56 in the same explosion chamber 28 that is seen at Figures 6 and 7. Said exhaust port is shown at Figure 8 (which shows positions 55 at the beginnings of the strokes of the piston) as always closed; the oppositely revolving valve shells 29 and 30 having just 60 reached their closing positions in the first diagram, and being just about to open said port 56 in the bottom diagram.

In Figure 9 the positions of the same parts are the same as at Figure 8, except 5 that Figure 9 shows the valve shells midway

of the respective strokes of the piston; the exhaust port 56 of the explosion chamber 28 being fully opened in the bottom diagram, and closed in the remaining diagrams.

In Figures 6 to 9 the same explosion 70 chamber 28 is shown, and the inner valve shell 29 is understood to be revolving always to the right, and the outer valve shell 30 always to the left. These figures therefore correspond to chests A and C at Figure 5. 75 Figure 12 corresponds to Figure 6, except that the outer valve shell 30 is understood to be revolving to the right, while the inner valve shell 29 revolves to the left; and the same is also true of Figure 13, as compared 80 with Figure 8, so that these Figures 12 and 13 correspond to chests at B and D of Figure 5, in engines in which the valve shells of one chest are directly geared to the valve shells in the adjoining chests, as at Figure 85 4. In other words, the inner and outer complementary valve shells in each chest may not only be made right and left, as in the perspectives at Figures 14 and 15, but they may also be right and left as compared 90 with the valve shells in the adjoining chests; the four valve shells in the chests A and B being therefore all dissimilar, but resembling those in C and D, respectively.

Suitable lag and lead may be provided, if 95 desired, at the beginnings or terminations of various piston strokes in a four-cycle engine, as, for example, a valve lag may be provided at the intake-valve opening (by shortening ports 64 and 66 at their leading 100 ends) of an extent equal to 15 degrees of motion of the crank shaft, as at Figure 10. This figure also shows provision (by lengthening ports 64 and 66 at their following 105 ends) of a valve lag at the closing of the intake stroke of the piston equal to 20 degrees of crank-shaft motion.

At Figure 11 (which shows the same 110 valve sections as Figure 10), there is also shown as an illustration a lag at the closing movement of the exhaust port (by lengthening ports 65 and 67 at their following ends) 115 of 10 degrees of crank-shaft motion; and there is also shown at this figure an exhaust-port lead at the opening of the exhaust (by lengthening ports 65 and 67 at their leading ends) equal to 30 degrees of the crank-shaft motion.

Variations may be resorted to within the 120 scope of the invention, and portions of the improvements may be used without others.

Having thus described my invention, I claim:

1. The combination with an engine-cylinder, of a head detachably mounted thereon, an explosion-chamber in said head and having intake and exhaust ports, valve means fitting around said explosion-chamber, means for continuously revolving said valve means, 125 a chest within which said valve means is 130

fitted, said chest having intake and exhaust ports, said explosion-chamber being hollow-walled, and provision being made for passage of cooling fluid therethrough, said detachable engine-head opening into the cylinders of an engine and comprising a fluid jacket in open communication with said explosion-chamber walls, and means for causing water to circulate through said detachable engine-head and said explosion-chamber walls.

2. The combination with an engine-cylinder, of a head detachably mounted thereon, an explosion-chamber in said head and having intake and exhaust ports, valve means fitting around said explosion-chamber, means for continuously revolving said valve means, a chest within which said valve means is fitted, said chest having intake and exhaust ports, said explosion-chamber being hollow-walled, and provision being made for passage of cooling fluid therethrough, said detachable engine-head opening into the cylinders of an engine and comprising a fluid jacket in open communication with said explosion-chamber walls, an engine-cylinder block having a fluid jacket in communication with said engine-head, and means detachably securing said head upon said block.

3. The combination with a set of engine-cylinders, of a single casting forming a detachable engine head and comprising a row of valve chests, each containing a dome forming a combustion chamber, intake and exhaust manifolds between which the row of valve chests extends, each valve chest having ports opening into the manifolds on its opposite sides, valves fitting between the combustion chambers and the chests, and each comprising oppositely-revolving ported shells, means for revolving the shells, the engine having a water-compartment, the walls of the combustion chamber being hollow, and means to force water from the compartment in the engine head through the combustion chamber walls.

4. The combination with a set of engine-cylinders forming a block, of an engine head detachably secured thereto and comprising a box-like structure forming a water jacket having a top spaced from its bottom, combustion chambers in the form of ported domes over said jacket and having hollow walls of which the outer wall merges into the top of the engine head, while the lower wall merges into the bottom thereof, and valves enclosing said combustion chambers and cooled by the water flowing between the walls thereof.

5. The combination with a set of engine-cylinders forming a block, of an engine head detachably secured thereto and comprising a box-like structure forming a water jacket having a top spaced from its bottom, com-

bustion chambers in the form of ported domes having hollow walls of which the outer wall merges into the top of the engine head, while the lower wall merges into the bottom thereof, valves enclosing said combustion chambers and cooled by the water flowing between the walls thereof, and ported chests enclosing said valves and fitted thereto, said domes and chests rising above said water jacket.

6. The combination with an engine-cylinder, of a head detachably mounted thereon, a ported explosion chamber and a ported valve chest in said head, a valve inserted to operate as a shutter between the chamber and the chest, said valve in the form of turret-like ported complementary nested shells, and means for revolving said shells continuously in opposite directions, the ports in said explosion chamber including ports in different zones upon one side thereof and including a port in an intermediate zone upon the opposite side thereof, the ports upon one side opposed to the porting upon the other side to balance the gas pressure evenly upon the inner shell, and the ports in the valve shells being correspondingly placed.

7. The combination with a detachable engine-head provided in its base with a water-compartment and also having an explosion chamber rising above said water-compartment and having intake and exhaust ports, of valve means revolving around said explosion chamber, a chest within which said valve means is fitted, said chest above said water-compartment and having intake and exhaust ports, said explosion chamber being hollow-walled, and provision being made for circulation of cooling fluid from said water-compartment therethrough, a discharge pipe rising from the top of the explosion chamber, a main connected to the discharge pipe for communicating with the usual radiator, and an inlet opening into said water-compartment.

8. The combination with an engine-cylinder, of a head having a water-compartment detachably mounted on said engine-head, an explosion chamber in said head and having intake and exhaust ports, complementary ported shells fitted one within the other to form a composite valve fitting around said explosion chamber, means for continuously revolving said shells in opposite directions, a chest in said head within which said composite valve is fitted, said chest having intake and exhaust ports, said explosion chamber being hollow-walled, and provision being made for circulation of cooling fluid therethrough and though said compartment, a discharge pipe rising from the top of the explosion chamber, and a main connected to the discharge pipe for communicating with the usual radiator, said discharge pipe serving as a bearing, a hub connected to one of

said shells and turning upon said bearing, a driving gear upon said hub, and a bearing for the other shell upon said hub.

9. The combination with an engine-cylinder, of an explosion chamber having intake and exhaust ports, opposite to each other, of complementary ported shells fitted one within the other to form a composite valve fitting around said explosion chamber, means for continuously revolving said shells in opposite directions, a chest within which said composite valve is fitted, said chest having intake and exhaust ports opposite to each other, the area of the inlet port in the explosion chamber being substantially equal to the area of its outlet port, and one of said ports being divided into two equal portions spaced apart so as to occupy different zones one above and one below the other port, securing balance of gas-pressure.

10. The combination with an engine-cylinder, of an explosion chamber having intake and exhaust ports, complementary ported shells fitted one within the other to form a composite valve fitting around said explosion chamber, and means for continuously revolving said shells in opposite directions, the ports being placed substantially in angular juxtaposition in each valve shell, with its exhaust port immediately following its intake port, and the explosion chamber having its intake and exhaust ports diametrically opposite each other, and one of them divided into two portions, one portion above and the other below the opposite port, giving pressure-balance.

11. The combination with a set of engine-cylinders, of a detachable head therefor provided with a water-compartment, a series of explosion-chambers in said head, each provided with a hollow wall communicating with said water-compartment, means for effecting a circulation of water through said water-compartment and the hollow walls of said chambers, each explosion-chamber having completely pressure-balanced ports, pairs of complementary ported shells fitted one within the other forming composite valves fitting around said explosion-chambers, ported chests in said head in which said valves are fitted, and means for continuously revolving the shells in opposite directions in each of said valves.

12. The combination with a set of engine-cylinders, of a detachable head therefor provided with a water-compartment, a series of explosion-chambers in said head, each provided with a hollow wall communicating with said water-compartment, means for effecting a circulation of water through said water-compartment and the hollow walls of said chambers, each explosion-chamber having completely pressure-balanced ports, pairs of complementary ported shells fitted one within the other forming composite

valves fitting around said explosion-chambers, ported chests in said head in which said valves are fitted, means for continuously revolving the shells in opposite directions in each of said valves, and spark-plugs in said detachable head communicating with the interiors of said explosion-chambers and extending to the exteriors of said detachable head.

13. The combination with a set of engine-cylinders, of a detachable head therefor provided with a water-compartment, a series of explosion-chambers in said head, each provided with a hollow wall communicating with said water-compartment, means for effecting a circulation of water through said water-compartment and the hollow walls of said chambers, each explosion-chamber having an intake-port and an opposite exhaust-port, pairs of complementary ported shells fitted one within the other forming composite valves fitting around said explosion-chambers, and means for continuously revolving said shells in opposite directions in each of said valves; one of the ports in each chamber being divided into upper and lower portions, one of said portions above and the other of said portions below the opposite port, evenly balancing the gas-pressure upon the inner of said shells.

14. The combination with a set of engine-cylinders, of a detachable head therefor provided with a compartment for cooling fluid, a series of explosion-chambers in said head provided with a hollow wall communicating with said compartment, means for causing cooling fluid to flow through said compartment and said hollow walls, each explosion-chamber having an intake-port and an exhaust-port, said parts opposite each other in said chamber, sets of complementary ported shells fitted one within the other forming a composite valve fitting around said explosion-chambers, said ports being completely gas-pressure balanced, preventing the valves from being subjected to friction during the compression and explosion strokes of the engine, and means for continuously revolving the shells in opposite directions in each of said valves.

15. The combination with a set of engine-cylinders, of a detachable head therefor provided with a water-compartment, a series of explosion-chambers in said head, each provided with a hollow wall communicating with said water-compartment, means for effecting a circulation of water through said water-compartment and the hollow walls of said chambers, each explosion-chamber having completely pressure-balanced ports, pairs of complementary ported shells fitted one within the other forming composite valves fitting around said explosion-chambers, ported chests in said head in which said valves are fitted, and means for continuously re-

volving the shells in opposite directions in each of said valves, said water-compartment being in the base-portion of said engine-head, and said explosion-chambers and said 5 chests rising therefrom.

16. The combination with a set of engine-cylinders, of a detachable head therefor provided with a fluid-compartment, a series of explosion-chambers in said head, each provided with a hollow wall communicating with said fluid-compartment, means for effecting a circulation of cooling fluid through said fluid-compartment and the hollow walls of said chambers, each explosion-chamber 10 having completely pressure-balanced intake and exhaust ports, pairs of complementary ported shells fitted one within the other forming composite valves fitting around said explosion-chambers, a row of ported chests 15 in said head in which said valves are fitted, said fluid-compartment being in the base-portion of said engine-head, and said explosion-chambers and said chests rising therefrom, and intake and exhaust manifolds 20 integral with said chests, the row of chests extending between said manifolds, means being provided above said explosion-chambers and chests for revolving the shells in each 25 pair in opposite directions.

30 17. The combination with a set of engine-cylinders, of a detachable head therefor provided with a water-compartment, a series of explosion-chambers in said head, each provided with a hollow wall communicating 35 with said water-compartment, means for effecting a circulation of water through said water-compartment and the hollow walls of said chambers, each explosion-chamber having completely pressure-balanced ports, pairs 40 of complementary ported shells fitted one within the other forming composite valves fitting around said explosion-chambers, ported chests in said head in which said valves are fitted, said shells in the form of turrets, 45 each having a top and a relatively small bearing-hub at said top, one hub within the other, means upon the inner hub to drive the inner shell, and means at the hub of the outer shell to drive it in the opposite direction.

50 18. The combination with an engine-cylinder, of a hollow-walled ported valve-seat having a central explosion-chamber for said engine-cylinder, a rotary valve-shell fitted around said valve-seat, ports in said valve-seat opening inwardly into said explosion-chamber and outwardly through the valve to intake and exhaust conduits, said valve-seat having inner and outer walls, and 55 a water-conduit, and means to cause water from said conduit at one end of the valve to circulate between said inner and outer walls within said valve, and to flow out of said seat at the same end of the valve.

60 19. The combination with an engine-cylind-

der, of a hollow-walled ported valve-seat having a central explosion-chamber for said engine-cylinder, a rotary valve-shell fitted around said valve-seat, ports in said valve-seat opening inwardly into said explosion-chamber and outwardly through the valve to intake and exhaust conduits, said valve-seat having inner and outer walls, and a water-conduit having separated walls from one of which said outer wall extends, and from another of which said inner wall extends, said inner wall protruding beyond the outer wall, and means to cause water from said conduit at one end of the valve to circulate between said inner and outer walls within 70 said valve, and to flow out of said seat at the same end of the valve.

20. The combination with an engine-cylinder, of a hollow-walled ported valve-seat having a central explosion-chamber for said engine-cylinder, a rotary valve-shell fitted around said valve-seat, ports in said valve-seat opening inwardly into said explosion-chamber and outwardly through the valve to intake and exhaust conduits, the ports being on opposite sides of said seat and the port-area on one side being equal to that on the opposite side and evenly distributing the pressure upon the revolving valve to balance the pressure at all portions of the length of the valve, said valve-seat having inner and outer walls, and a water-conduit, and means to cause water from said conduit at one end of the valve to circulate between said inner and outer walls within said valve, and to flow out of said seat at the same end of the valve.

25 21. The combination with an engine-cylinder, of a hollow-walled ported valve-seat having a central explosion-chamber for said engine-cylinder, a rotary valve-shell fitted around said valve-seat, ports in said valve-seat opening inwardly into said explosion-chamber and outwardly through the valve to intake and exhaust conduits, the ports being on opposite sides of said seat and the port-area on one side being equal to that on the opposite side and evenly distributing the pressure upon the revolving valve to balance the pressure at all portions of the length of the valve, said valve-seat having inner and outer walls, and a water-conduit, and means to cause water from said conduit at one end of the valve to circulate between said inner and outer walls within said valve, and to 100 flow out of said seat at the same end of the valve.

105 22. The combination with an engine-cylinder, of a valve-seat having a central explosion-chamber and ported upon opposite sides, and a rotatable ported valve fitted around said seat; one of the ports in said 110

seat being divided into upper and lower portions, one of said portions above and the other below the opposite port, evenly balancing the gas-pressure upon said valve.

23. The combination with an engine-cylinder, of a valve-seat having a central explosion-chamber and ported upon opposite sides, and a rotatable ported valve fitted around said seat; one of the ports in said

10
seat being divided into upper and lower portions, one of said portions above and the other below the opposite port, evenly balancing the gas-pressure upon said valve, said valve having correspondingly divided separate intake and exhaust ports, the ports in said seat being common to the intake and exhaust ports in the valve.
